UNITED STATES PATENT OFFICE

164,426

CLOTHES RACK

Thomas J. Kelleher, Chicago, Ill.

Application May 16, 1950, Serial No. 9,970

Term of patent 3½ years

(Cl. D33—8)

To all whom it may concern:

Be it known that I, Thomas J. Kelleher, a citizen of the United States, residing at Chicago, in the county of Cook and State of Illinois, have invented a new, original, and ornamental Design for Clothes Racks, of which the following is a specification, reference being had to the accompanying drawing, forming part thereof.

Fig. 1 is a perspective view of a clothes rack, showing my new design;

Fig. 2 is a fragmentary enlarged sectional view taken along the line 2—2 of Fig. 1; Fig. 3 is a fragmentary enlarged sectional view taken along the line 3—3 of Fig. 1; and Fig. 4 is a fragmentary elevational view taken along the line 4—4 of Fig. 1.

I claim:

The ornamental design for a clothes rack, as shown.

THOMAS J. KELLEHER.
